DISPENSING CONTAINER

James R. Bedell, Cuyahoga Falls, Ohio, assignor
to The B. F. Goodrich Company, New York,
N. Y., a corporation of New York

Application July 7, 1936, Serial No. 89,333

1. Claim. (Cl. 206—31)

This invention relates to containers and more especially to containers manufactured from cardboard or other flexible sheet material.

The application is a continuation in part of my application Serial No. 47,836, filed November 1, 1935, and entitled "Dispensing container".

The principal objects of the invention are to provide a container which is of rectangular prismatic form when closed, but which may be adjusted to permit selective removal of articles without cutting or tearing the container; to provide a container of novel appearance; and to provide a combined shipping and dispensing container which may be manufactured from a single piece of material and may be shipped in collapsed condition and assembled without the use of glue.

Other objects will appear from the following description and the accompanying drawing.

Of the drawing:

Fig. 1 is a perspective view of the complete container, the top panel being shown in full lines to indicate its closed position and in dot and dash lines to indicate its position just prior to closing of the container, the dispensing apron being shown in open position.

Fig. 2 is a perspective view showing the front and side panels and the bottom of the container, the dispensing apron being closed.

Fig. 3 is a fragmentary section taken on line 3—3 of Fig. 1, the rear portion of the container being broken away.

Fig. 4 is a plan view of the sheet material before being folded into container form.

Fig. 5 is a perspective view of a partially folded container illustrating the manner of assembling the device.

Referring to the drawing:

The container is formed from a single sheet of cardboard or other similar material which is cut to the shape illustrated in Fig. 3 and is scored along the dash lines indicated thereon to form a front panel 11, a rear panel 12, side panels 13, 14, top panel 15, bottom panel 16, locking tabs 17, 18, 19 and 20, a dispensing apron 21 having wings 22 and 23, and glue flap 24 and locking flap 25.

A window opening 26 is preferably formed in the front panel 11 and may be covered by a transparent pane 27 of cellophane or similar transparent material.

A dispensing notch 28 is cut from the lower end of the bottom panel 11 so as to leave a panel supporting leg at each side thereof adapted to be supported from the bottom panel, the notch

being adapted to permit withdrawal of articles from the container.

The panels 13, 12 and 14, 11 are located adjacent each other, in the order named, from one end of the blank to the other and are connected to each other at the parallel score lines 29, 30 and 31, and the fourth score line 32, parallel to score lines 29, 30 and 31, defines the boundary line between panel 11 and glue flap 24. Score lines 29 and 30 also provide the fold lines between the dispensing apron 21 and its wings 22 and 23. A score line 33, extending at right angles to score lines 29 and 30, provides the line of fold between panels 13 and 14 and their respective locking tabs 17 and 18, and the line of fold between front panel 11 and the top panel 15. The score line 34, parallel to score line 33, provides the line of fold between rear panel 12 and bottom panel 16 and also provides the line of fold between the side panels 13 and 14 and their respective bottom tabs 19 and 20. Score line 35, also parallel to score line 33, provides the line of fold between the dispensing apron 21 and the bottom panel 16, and the score line 36, also parallel to score line 33, provides the line of fold between the top panel 15 and its flap 25.

With the exception of the window pane 27 the entire article is formed from an integral blank which may be produced in a single operation by cutting dies, which dies also score the material where desired.

A pair of slots 37, 38 are formed on the blank in line with the score lines 31 and 32 and in the front panel 11 to accommodate the wings 22 and 23 of the dispensing apron 21. The tabs 17 and 18 are formed respectively with integral interlocking fingers 39 and 40 and the lower tabs 19 and 20 are similarly formed with fingers 41 and 42. These pairs of fingers are adapted to interlock in the well known manner illustrated in Fig. 2.

In assembling the container the side panels 13 and 14 are folded inwardly on lines 29 and 30 toward each other and the fingers 41 and 42 of the lower tabs 19 and 20 are interlocked as shown in Fig. 2 under the bottom panel 16 so as to firmly support the panel 16 in position without the use of glue. The wings 22 and 23 of the apron 21 are folded inwardly and the apron 21 is folded slightly to bring the wings 22 and 23 inside of the container. The front panel 11 is then folded on line 31 and the glue flap 24, which has been coated with an adhesive, is folded inwardly and adhered to the inside of the front margin of panel 13. The dispensing apron 21 is then folded

against the front panel 11 to close the dispensing notch 28. In this position the container is ready to be filled. After being filled the fingers 39 and 40 of the tabs 17 and 18 are interlocked, the top panel 15 is folded along score line 33 over the tabs 17 and 18 and its flap 25 is tucked under the tabs 17 and 18 to provide a closed container. In this condition the container is in the form of a parallelopiped so that a plurality of such containers may conveniently be packed for shipment with economy of space.

When it is desired to remove articles from the container the dispensing apron 21 may be pulled forward to the position shown in Fig. 1, such movement being limited by lugs 43, 44 formed integrally with the wings 22, 23 and the articles in the container may be withdrawn through the notch 28. The inclination of the dispensing apron 21, in its open position, being at an acute angle to the front panel 11 of the container the undesired flow of articles from the container is prevented. The arcuate form of the tabs 22 and 23 insures their accurate fit within the slots 37, 38 so as to prevent accidental escape of the contents by way of such slots at all times. The locking of the tabs 19, 20 below the smooth floor 16 insures against such sagging of the floor under the load of the contained material as to disturb

the relation of the arcuate tabs in the slots without the use of glue.

Where desired the single glue joint between the glue tab 24 and the panel 13 may be made first and the entire carton may then be shipped in a flat collapsed condition by simply folding on lines 30 and 32.

I claim:

A container formed of one piece of sheet material and comprising a collapsible box-like structure having a back panel, a bottom panel and two side panels hinged thereto, a front panel integral with and hinged to one of the side panels and having a glue flap adapted to be attached to the other side panel, said front panel having a dispensing opening narrower than the panel and a pair of guide slots spaced laterally therefrom and extending to its lower margin so as to define with said opening a pair of panel-supporting legs adapted to be supported from the bottom panel, said bottom having a dispensing hopper hinged thereto with arcuate end tabs formed for limited sliding engagement in said slots, said side panels being formed with interlocking means and being adapted to be locked together beneath said bottom panel so as to support the bottom against sagging, said container being formed with integral means for closing its upper end.

JAMES R. BEDELL.
